WELDED EXHAUST PIPE

Otto H. Brauer, Three Rivers, Mich., assignor to
 Fairbanks, Morse & Co., Chicago, Ill., a corporation of Illinois

Application August 25, 1938, Serial No. 226,692

1 Claim. (Cl. 60—31)

This invention relates to conduit structures and more particularly to a fabricated conduit assembly adapted as an exhaust discharge pipe for internal combustion engines and the like.

5 The principal purpose of the invention is to provide an improved, fabricated exhaust pipe for engines of the type generally employed for motivating railway motor cars and the like, the improvements attained being found in a fabricated, 10 sheet-metal exhaust pipe comprising a minimum number of parts which are pre-formed and assembled together as by welding.

Another object is to provide a relatively light-weight, fabricated exhaust pipe of substantially rigid construction which may be manufactured at low cost and which requires a minimum number of forming and assembly operations.

Further objects and advantages will readily appear from the following description and from 20 the accompanying drawing, in which:

Fig. 1 is a plan or top view of a preferred embodiment of the invention, a portion of the conduit structure being broken away to illustrate certain structural features thereof; Fig. 2 is a 25 side elevation of the conduit shown in Fig. 1; Fig. 3 is an end elevation of the conduit, as viewed from the discharge end thereof, and Fig. 4 is a transverse sectional elevation of a portion of the conduit, as taken along line 4—4 in Fig. 2.

30 Referring to the drawing by suitable reference characters, the improved exhaust conduit which is particularly adapted to internal combustion engines employed for providing the motive power for railway motor cars and the like, includes

35 an angulate, sheet metal member 10 substantially U-shape in section, the member being formed preferably from thin plate steel, as by stamping and pressing the plate stock to the desired shape. Thus the member provides a rear 40 wall 11 and side walls 12 which cooperate with other elements of the structure hereinafter to be described, to form the conduit.

Projecting from the open side of the member 45 10 opposite the wall 11, is a relatively deep channel member 13 which, like member 10, may be formed from thin sheet steel stock as by a stamping and pressing operation. The member 13 provides a top wall 14 and side walls 15 for the major 50 length of the conduit. In forming the member 13, as by stamping, the side walls 15 are tapered somewhat, in the direction of the exhaust discharge end 16 of the conduit. Also, end portions 55 of the side walls 15 adjacent the opposite end of the member are cut away as shown, leaving

flanges 17 and end portions 18 by which the member 13 may be secured to the member 10.

In the assembly of members 10 and 13, the forward vertical marginal portions 19 of side walls 12 which form part of member 10, and the inclined upper margins 20 of the same side walls overlap respectively, the ends 18 of side walls 15 and the flanges 17 on member 13. It is to be noted that in forming member 13, the rearward end portion 21 is turned upwardly, being bent 10 along a transverse line 22 which is substantially in register with the edges of side wall ends 18. The degree of upward inclination thereof relative to the remainder of member 13, is, by preference, in the present example, such that the top 15 surface of the portion 21 may lie flush with the inclined edges of wall margins 20 on member 10, while the remainder of the member 13 projects from member 10 at an angle to the horizontal. The inclination of conduit member 13 to the horizontal will depend upon particular installations 20 of the exhaust duct, and in certain instances it may be desirable to arrange the member 13 in a horizontal position.

After the members are so related, the lapped 25 margins and flanges above described, are preferably secured together as by spot-welding such as indicated at points 23. Spot-welding the members together, while effecting a secure and rigid connection, provides for greater economy and 30 quicker assembly over bolting or a continuous weld along the margins, although the latter methods of securement may be employed if desired.

The bottom closure for the conduit is provided 35 by a relatively shallow channel member 24 which, like the other members, may be formed from thin sheet steel stamped and pressed into the desired shape. The bottom member is inserted between the respective side walls 12 and 15 of the members 40 10 and 13, with its sides or legs 25 overlapped by the lower margins of the said side walls. Thus the wall portion 26 which forms the bottom of the conduit, lies inwardly or upwardly of the lower side wall edges, leaving the sides 25 clear 45 for securement to the wall margins, as by spot-welding at the points 27. The rear end portion 28 of the bottom member is turned down to provide an additional flange which may be spot-welded to the lower portion of the wall 11 on member 10. It will be noted from Fig. 2 that in the final assembly relation of the parts, lower marginal portions 29 of walls 11 and 12 project 50 below the adjacent section of bottom member 24. Although it is preferred to leave these wall por- 55

tions as shown, as they contribute to the rigidity of the structure, nevertheless they may be removed or cut away if desired. However, this would require additional operations which would 5 add somewhat to the production costs, and hence for this reason these wall portions may be left on the structure.

The upper margin of top wall portion 21 of member 13 is spaced from the upper margin 10 of wall 11 and these margins together with the upper margins of the side walls 12 define an inlet port 30. Overlying these margins and secured thereto, as by welding at 31, is a plate 32 provided with an opening 33 in register with port 15 30. The plate is further provided with bolt-receiving apertures 34 for securing bolts (not shown) which serve to attach the conduit structure to the engine (not shown) with the aperture 33 and port 30 in register with the cylinder 20 exhaust port (not shown).

It will now appear that the several members cooperate in forming a conduit passage 35 leading from the inlet port 30 to the discharge port 36 in the conduit end 16. The structural arrangement and assembly of the elements is such 25 as to divide the passage 35 into a chamber 37 of substantial sectional area located adjacent the inlet port 30 and a conduit passage 38 of lesser sectional area, located between the chamber and 30 discharge port 36, the latter passage converging toward the port 36. The chamber 37 serves as an expansion chamber wherein the exhaust gases may become cooled to a certain extent before discharge through passage 38, the cooling 35 of the gases resulting in an advantageous reduction in engine cylinder back pressure. It will be observed from Fig. 2, that the conduit passage 35 between the inlet and outlet ports, comprising the chamber 37 and passage section 38, 40 is of angulate trend as preferred in the present example.

From the foregoing it will now appear that the exhaust conduit structure comprises but four elements which are preformed and assembled together by welding, the resulting assembly being rigid and durable. Further, the conduit structure requires but a minimum of forming operations on its parts as well as a minimum of assembly operations, thus enabling production of the conduit at considerably reduced cost. 5

The present disclosure relates particularly to 10 a preferred embodiment of the invention, but it is to be understood that alterations or modifications in the parts and assembly thereof may be readily effected as desired, without departing from the spirit and intended scope of the invention as defined by the appended claim. 15

I claim:

An exhaust discharge conduit device for an internal combustion engine, comprised of wall-forming elements preformed of relatively thin sheet metal, welded together to provide a unitary conduit structure, said elements including a U-shaped element, a relatively deep channel element projecting outwardly from the open side of said U-shaped element and provided with a flanged extension spanning a portion of the open side of said U-shaped element, and a relatively shallow channel element disposed within the open side of said deep channel element and cooperating therewith to form a conduit passage 20 tapering toward one end thereof, said last mentioned channel element having an end portion projecting inwardly of said U-shaped element, said end portion and said flanged extension 25 cooperating with the U-shaped element to form 30 a chamber in communication with said conduit passage, the chamber so formed having a major sectional area greater than the greatest sectional area of said conduit passage. 35
